US00D476682S

(12) **United States Design Patent** (10) Patent No.: **US D476,682 S**
 Berry et al. (45) Date of Patent: ** Jul. 1, 2003

(54) **BINDER**

(75) Inventors: **Stephen D. Berry**, Plainfield, IL (US); **John C. Olson**, Chicago, IL (US); **Earle Cramer**, Chicago, IL (US); **Scott Kouri**, Chicago, IL (US); **Eric B. Heitmann**, Kenosha, WI (US); **Stephen P. Corr**, Gurnee, IL (US); **Josh P. Goldfarb**, Newport Beach, CA (US)

(73) Assignee: **ACCO Brands, Inc.**, Lincolnshire, IL (US)

(**) Term: **14 Years**

(21) Appl. No.: **29/152,897**

(22) Filed: **Nov. 9, 2001**

(51) **LOC (7) Cl.** **19-04**

(52) **U.S. Cl.** **D19/27; D19/26**

(57) **CLAIM**

We claim the ornamental design for a binder, as shown and described.

DESCRIPTION

FIG. 1 is a perspective view of a binder embodying the present invention.

FIG. 2 is front view of the binder.

FIG. 3 is a left side view of the binder.

FIG. 4 is a top view of the binder.

FIG. 5 is a bottom view of the binder.

FIG. 6 is a perspective view showing the binder in the open position; and,

FIG. 7 is an enlarged partial view of the left side of the binder, with the binder shown in the open position.

The portions of the binder in broken lines are shown as environment or for illustrative purposes only and form no part of the claimed design.

1 Claim, 4 Drawing Sheets
